UNITED STATES PATENT OFFICE

GEORGE E. BALDWIN, OF HOLTON, KANSAS

DRAG

Application filed November 19, 1927. Serial No. 234,520.

My present invention relates to a rotatable road drag and scraper of a construction whereby all the surfaces of a road will be engaged and distributed evenly to produce a smooth road surface and obviate the unsatisfactory leaving of piles of dirt in the road which is true with respect to ordinary road drags and graders.

A further object is the provision of a combined road drag and scraper that includes a substantially triangular frame having circular drags journaled at the front and at the rear corners thereof, and whereby the rear drags, incident to their arrangement from the point of draft of the machine and weights imposed thereon will be caused to rotate to direct the dirt from the road to be raked and spread to produce a smooth and even surface.

A still further object is the provision of a road drag of this type in which spring influenced adjustable means is provided for influencing the drags into road contacting position and wherein weighted means that include rollers carried by the spring influenced means, the said rollers on the weighted means traveling over one side and over the rear of the upper faces of the drags for holding said drags in road contacting engagement to cause the rotation of the drags and likewise wherein in the weighted roller carrying means limits the upward canting of the rear portions of the drags and obviates any liability of injury thereto should the same contact with stones and other obstructions in the road surface.

A still further object is the provision of a combined road drag and scraper of a construction to facilitate the ready movement thereof over a road surface.

For a full and comprehensive understanding of the improvement reference is to be had to the drawings which accompany and form part of this application.

In the drawings:

Figure 1 is a top plan view of a combined road drag and scraper in accordance with this invention.

Figure 2 is a side elevation thereof.

Figure 3 is a sectional view approximately on the line 3—3 of Figure 1.

Figure 4 is a detail sectional view approximately on the line 4—4 of Figure 3.

Figure 5 is a sectional view substantially similar to Figure 4 but showing a scraper blade on one of the arms or spokes of the drag. 55

Figure 6 is a perspective view of one of the scraper blades.

Figure 7 is a detail sectional view approximately on the line 7—7 of Figure 1.

My improved road drag or road surfacing 60 device may be adjustably supported on a wheeled frame.

In the showing of the drawings, the drag includes a substantially triangular or V-shaped frame, the straight rear portion of 65 which for distinction being indicated by the numeral 1 and the angle sides by the numeral 2. The frame is preferably constructed of angle irons, the sides and the rear portion thereof being bolted, riveted or otherwise fixedly 70 connected and one or more transverse brace members 3 connecting and properly spacing the sides 2. The front or apex of the frame has attached thereto a pivotally supported hitch 4 designed to be attached to a tractor or 75 other propelling means.

The frame, at the front thereof and at the rear corners thereof supports thereon flanged bearing sleeves. As each of these bearing sleeves are of a similar construction each is 80 in the drawings indicated by the numeral 5. The flanged portions of the bearing sleeves are in contact with the under face of the frame and the said bearing sleeves are, of course, rigidly secured to the frame. The 85 under face of each bearing sleeve is provided with a race-way for anti-frictional elements 6 and passing centrally through each bearing sleeve there is a stub shaft 7 that also passes loosely and freely through a bearing opening 90 in the central and hub portions 8 of the circular drags 9. The hubs 8 have a race-way in which the anti-frictional balls 6 are received. The stub shafts are removably secured to the under face of the hubs 8 by means 10. The 95 loose and free mounting of the drags on the stub shafts allows a certain amount of tilting and canting of said drags.

The rim of each of the circular drags 9 is for distinction indicated by the numeral 11, 100

and the spokes which radiate from the hub to the rim and connect these elements are indicated by the numeral 12. Each spoke 12 is in the nature of an angle iron and the 5 lower flanges of the angle irons are indicated for distinction by the numerals 13. There are passed through openings in the flanges 13 equidistantly spaced rods that provide teeth 14, the said teeth resting against the inner 10 faces of the vertical flanges of the spokes and preferably having their upper ends offset and passing through openings in said flanges. The offset ends of the teeth are preferably threaded and are engaged by nuts 15.

15 The vertical flanges of the spokes, below the openings through which the offset ends of the teeth 14 pass are provided with other openings for the reception of securing means 16 for blades 17. The blades 17 may be employed in connection with the teeth or independently thereof.

In order to more effectively hold the drags in road engagement I secure upon the rear member 1 of the frame spaced upwardly directed rods 18 that pass through openings in a metal beam 19. The outer or upper ends of the rods are threaded, and have screwed thereon nuts 20. Surrounding the rods and contacting with the beam 19 and the nuts 20 25 there are helical springs 21. The ends of the beam are inclined downwardly and are formed with the stub shafts 22 for rollers 23. These rollers as disclosed by the drawings are in contact with the upper face of 30 the rims 11 of the circular drags adjacent to the outer edges of said drags and consequently exert a pressure upon these portions of the drags to force the outer teeth into greater ground contacting engagement than the inner teeth of the drags.

40 The rods 25 are pivotally connected to the vertical flanges of the side members 2 of the frame and loosely connected to the beam 19 and afford brace means for the said beam and likewise brace means for the sides of the frame.

Hingedly secured to what I will term the inner side member 2 of the frame, at the front thereof, as indicated by the numeral 26, there 45 is a plate 27 which is disposed transversely over the top of the said front of the frame. A rod or bolt member 28 is secured to the frame and passes through an opening in the plate 27. This rod or member is really in 50 the nature of a bolt and is similar to the rods or bolts 18, the same having screwed on its outer end a nut 21 that compresses a helical spring arranged on the rod or bolt 28 against the plate 27. The outer end of the plate has 55 either secured thereto or formed therewith a downwardly extending portion that merges into a stub shaft on which there is journaled a roller 30 that is in contacting engagement with the under face of what I will term the 60 outer side of the rim of the front drag. A 65

pivotaly supported brace rod 31 is loosely connected to one side of the frame and to the plate 27, as clearly disclosed by Figures 1 and 2 of the drawings. The drags are loosely mounted upon their stub shafts and, therefore, liable to a free turning and to a canting movement thereon. By reference to Figure 3 of the drawings it will be seen that the weighted and spring influenced frame 1 carries the wheels that contact with the outer and rear faces of the rim of the drag to impart a slight canting or angle movement to the drag end or outer teeth of the frame. It will thus be noted that the outer and rear teeth of the drags are brought into greater contact with the road surface than the inner and forward teeth of the said drags and it is by virtue of such contact that the drags are caused to rotate. The weight imparted to the top of the back part of the rotating drags is so arranged as to prevent the rotating drags from flying up in the event of the front portions thereof striking any perceptible elevation in the ground surface and the tension springs on the top afford a relief to the drag so contacted that the breakage thereof will be prevented.

The direction of the turning of the front and rear drags is indicated by the arrows in Figure 1.

95 The rollers that engage the rear portions of the rear drags are for distinction indicated by the numeral 32 and are journaled on stub shafts on the ends of members 33, the said members extending from the rear member 1 of the frame. The roller for the rear of the front drag is indicated by the numeral 34 and is journaled on the spindle of a member 35 that is secured to the transverse brace element 3.

100 The improvement is of a comparatively simple nature and may be cheaply manufactured and easily operated. Of course, the frame may be provided with a seat for the operator which, of course, is especially desirable should the drag be drawn by draft animals but preferably the drag is of such weight and size that the employment of a tractor for pulling the same will be required. The construction and advantages of the improvement will, 105 it is thought, be understood and appreciated by those skilled in the art to which such invention relates.

Having described the invention, I claim:

1. A road drag comprising a substantially 110 triangular frame having a draft hitch at the apex thereof, circular drags loosely and freely journaled at the front and at the rear corners of the frame, each of said drags including an inner hub portion and an outer 115 rim portion and radially disposed angle spokes connecting the hub and rim, said spokes having their horizontal flanges provided with spaced openings and their vertical 120 flanges provided with similar openings, a 125

- tooth passing through each of the vertical openings and having an offset end received through the horizontal openings, means for removably securing the teeth on the spokes, 5 spring influenced means carried by the frame and contacting with the upper faces adjacent to the outer portions of the rims of the drags for canting and influencing the outer teeth of the drags into ground contacting engagement and means contactable with the rims at the rear of the drags for limiting the upward canting of such portions of the drags beyond a predetermined degree when such drags meet with an obstruction. 10
- 15 2. A road drag comprising a substantially triangular frame having a draft hitch at the apex thereof, circular drags loosely and freely journaled at the front and at the rear corners of the frame, each of said drags including an inner hub portion and an outer rim portion and radially disposed angle spokes connecting the hub and rim, said spokes having their horizontal flanges provided with spaced openings and their vertical flanges 20 provided with similar openings, a tooth passing through each of the vertical openings and having an offset end received through the horizontal openings, means for removably securing the teeth on the spokes, scraper blades removably secured to the spokes of the drags, weighted spring influenced means carried by the frame and having rotatable elements for contacting with the upper faces adjacent to the outer portions of the rims of 25 the drags for canting and influencing the teeth on such portions of the drags into ground contacting engagement and rotatable elements carried by said means contactable with the rims at the rear of the drags for limiting the upward swinging of such portions of the drags when such drags meet with an obstruction. 30
- 35 3. A road drag comprising a substantially triangular frame having a draft hitch at the apex thereof, circular drags loosely and freely journaled at the front and at the rear corners of the frame, each of said drags including an inner hub portion and an outer rim portion and radially disposed angle spokes 40 connecting the hub and rim, said spokes having their horizontal flanges provided with spaced openings and their vertical flanges provided with similar openings, a tooth passing through each of the vertical openings and having an offset end received through the horizontal openings, means for removably securing the teeth on the spokes, members carried by the frame, spring means influencing the members in the direction of the 45 frame, adjusting means for said spring means, rollers journaled on the ends of said members contacting with the upper faces adjacent to the outer edges of the circular drags for canting the drags, rearwardly extending members carried by the frame, and rollers 50
- 55 60 65
- journalized on said last mentioned members and disposed over but above the rear portions of the circular drags for the purpose set forth. In testimony whereof I affix my signature. GEORGE E. BALDWIN. 70
